CLAIM

(52) **U.S. Cl.**

The ornamental design for a high brightness LED package, as shown and described.

USPC **D26/1**

DESCRIPTION

(58) **Field of Classification Search**

FIG. 1 is a top perspective view of a high brightness LED package showing our design;

USPC D26/1-4; 313/313, 315, 316, 317, 318;
315/52, 53, 56, 57, 58

FIG. 2 is a side view thereof;

See application file for complete search history.

FIG. 3 is a top view thereof;
